UNITED STATES PATENT OFFICE.

WALLACE D. KIMBALL, OF NEW YORK, N. Y., AND CHARLES G. MORTIMER, OF HARRISON, NEW JERSEY, ASSIGNEES, BY MESNE ASSIGNMENTS, TO NASHUA GUMMED & COATED PAPER COMPANY, OF NASHUA, NEW HAMPSHIRE, A CORPORATION OF MASSACHUSETTS.

STRAP FASTENER.

Original application filed March 1, 1917, Serial No. 151,634. Divided and this application filed February 8, 1919. Serial No. 275,812.

To all whom it may concern:

Be it known that we, WALLACE D. KIMBALL and CHARLES G. MORTIMER, both citizens of the United States, and residents of the city, county, and State of New York, and Harrison, Hudson County, New Jersey, respectively, have invented new and useful Improvements in Strap Fasteners, of which the following is a specification.

10 This invention relates to improvements in fasteners for bale bands and box straps and the sealed joints formed thereby, and has for its object to provide a strong and easily applied fastener which may be very 15 cheaply made and which will form a securely sealed joint in box straps and bale bands of the common kind.

The invention of this application constitutes an improvement on the joint and fastener disclosed in U. S. Patent No. 1,265,188, granted May 7, 1918 to E. E. Flora, the chief advantage of the present fastener being that it may be formed of sheet metal by a simple stamping operation whereby it may be 25 produced at a cost very little greater than the actual cost of the material, the fastener forming a joint quite as strong as the coiled wire joint of the Flora patent.

30 This application constitutes a division of our copending application Ser. No. 151,634, filed March 1, 1917, spliced joint for bale bands.

In the accompanying drawings we have 35 illustrated a preferred embodiment of the invention and also a modified structure.

In the said drawings,

Figure 1 is a perspective view of our preferred form of fastener;

Fig. 2 is a longitudinal section through 40 the fastener and the connected ends of the band or strap;

Fig. 3 is a transverse section on line 3—3 of Fig. 2;

Fig. 4 is a perspective view of the modified form of fastener; and

Fig. 5 is a longitudinal section through the modified form of fastener and the connected strap ends.

Referring to the drawings, particularly 50 to Figs. 1, 2 and 3, 1 and 2 indicate respectively two ends of the bale band or box strap to be joined by the fastener. The

fastener is formed of a strip of sheet metal somewhat wider than the straps and of a length three or four times its width. The 55 sheet metal strip is formed with a series of transverse slots 3 of a length equal to the width of the straps and terminating short of the edges of the sheet metal so that the fastener has continuous uncut margins 4 on 60 each edge.

The slots are preferably formed by cutting out a narrow piece of metal from each slot and the alternate bridge pieces 5 formed between the slots are pressed in opposite directions so that in the finished fastener, as shown in Fig. 1, there is an unobstructed 65 passage extending longitudinally of the fastener between the uncut margins of a depth sufficient for the ends of the strap or band 70 to be thrust in lapped relation between the staggered bridge pieces.

In applying the fastener to the straps the strap ends are assembled in the fastener in the manner described with every other 75 bridge piece lying on one side of the lapped strap ends and the alternate bridge pieces lying on the other side. The fastener and the assembled straps are then flattened by a hammer blow or preferably in a sealing 80 tool which tends to force the staggered bridge pieces back into the same plane, thereby clamping and corrugating the strap ends together in the manner shown in Fig.

2. The metal of the strap ends and the 85 fastener is sufficiently inelastic to be permanently distorted by the compression of the fastener, thereby interlocking and permanently fastening the parts so that the strap can be taken off only by destroying the fastener or cutting the strap.

Our improved fastener may be pressed until substantially flat without danger of rupturing the fastener, for the reason that the flattening pressure tends to restore the 95 sheet metal to its original shape rather than further bend it, as in the case of the coiled wire fastener of the Flora patent, and we have found in practice that a very strong joint may be secured with comparatively 100 light metal.

In our modified form of fastener the straps are not overlapped in the fastener as above described, but each strap end is se-

2
cured by a different part of the fastener, the purpose of which is to facilitate drawing the strap tightly around the box, as pointed out in our above mentioned copending application. As here shown the fastener comprises margins 7 with alternate staggered bridge pieces 8, the same as in the preferred modification. The fastener is, however, somewhat longer, and at approximately its middle point one of the bridge pieces has its edge turned up as shown at 9 to form a stop for one end of the box strap, that is, the box strap 2 thrust in from the left as shown in the drawing, and to also form a deflector 15 for the other end of the box strap to cause it when thrust into the fastener to be deflected through the slot adjacent the stop and beneath the other end of the fastener as shown in Fig. 5, in which the fastener is illustrated as attached to the straps. The stop 9 is easily formed in the manufacture of the fastener by suitably shaping the cutting die which cuts the slot in the middle to leave one edge uncut so that the piece 20 forming the stop will be turned up by the action of the die instead of punched out in the usual manner.

In applying this form of fastener to the strap the strap bands will be assembled in 30 the fastener in the manner described and drawn as tightly as can be done by hand. A stretching tool will then be applied to the ends of the band on each side of the fastener and the ends drawn together, thereby thrusting the end 3 of the band further under the opposite end of the fastener until the band or strap is drawn tightly against the box. While the strap is held tight by the stretching tool the crimper or sealing tool is applied or the fastener otherwise flattened to 35 40 crimp the parts together.

Claims:

1. A sealed joint comprising metal strips with permanent close corrugations and a 45 sealing fastener surrounding said strips, said sealing fastener having a pair of longitudinal members extending along the edge of the strips and transverse members connecting said longitudinal members, said

transverse members lying alternately in the 50 depressions on opposite sides of the corrugations in firmly compressed relation therewith and substantially in the same plane.

2. A sealing fastener for metal straps consisting of a single strip of sheet metal comprising a pair of longitudinal members, a series of spaced transverse members connecting said longitudinal members, said transverse members being alternately offset in opposite directions to provide an open passageway between the alternate transverse members for the reception of a flat box strap, the spaced transverse members at one side of said passageway being narrower than the spaces between the adjacent members at the other side of said passageway. 60

3. A sealing fastener for metal straps comprising a pair of longitudinal members, a series of spaced transverse members connecting said longitudinal members, said transverse members being alternately offset 70 in opposite directions to provide an open passageway between the alternate transverse members for the reception of a flat box strap, and means adjacent one of said transverse members for deflecting the end of one of the straps to be joined out of said passageway. 75

4. A sealing fastener for metal straps comprising a pair of longitudinal members, 80 a series of spaced transverse members connecting said longitudinal members, said transverse members being alternately offset in opposite directions to provide an open passageway between the alternate transverse members for the reception of a flat box strap, and means intermediate the ends of said fastener for stopping the end of one of the straps to be joined and deflecting the end of the other strap out of said passageway. 85 90

Signed at New York city, in the county and State of New York, this 7th day of December, 1918.

WALLACE D. KIMBALL.
